Primary Examiner — Karen E Eldridge Powers

(57) **CLAIM**

The ornamental design for a set of electric toothbrush and its charger as shown and described.

DESCRIPTION

1. Set of electric toothbrush and its charger

1.1 : Perspective

1.2 : Front

1.3 : Back

1.4 : Left

1.5 : Right

1.6 : Top

1.7 : Bottom

FIG. 1 is a perspective view of the claimed design; FIG. 2 is a front view of the claimed design; FIG. 3 is a back view of the claimed design; FIG. 4 is a left side view of the claimed design; FIG. 5 is a right side view of the claimed design; FIG. 6 is a top view of the claimed design; FIG. 7 is a bottom view of the claimed design.

1 Claim, 7 Drawing Sheets
